(57) **CLAIM**

The ornamental design for a door facing, as shown and described.

DESCRIPTION

FIG. 1 is a front perspective view of our design, with the rear perspective view being a mirror image thereof; and, FIG. 2 is a front elevational view of FIG. 1.

The broken lines in the figures represent portions of the door facing that form no part of the claimed invention.

1 Claim, 2 Drawing Sheets

FIG. 1

FIG. 2
